UNITED STATES PATENT OFFICE

WILLIAM L. LADEMANN, OF NEW YORK, N. Y.

OUTLET BOX SUPPORT

Application filed September 21, 1926. Serial No. 136,768.

The objects of this invention are to provide means for supporting outlet boxes, switch boxes and the like from the steel bucks which have come into such general use for door frames, window frames, etc., and to furnish such means in a simple, inexpensive and thoroughly practical form, readily attachable to the buck and adapted to provide a firm, rigid support for holding the switch box or other device in the desired position.

The invention embodies a number of novel features of construction, combinations and relations of parts, as will be clear from the following specification, including the drawing accompanying and forming part of the same.

Figure 1 is a plan view of a supporting bracket embodying the invention, shown applied to the vertical leg of a steel buck and having a portion of the supporting arm and the box applied thereto shown in section.

Figure 2 is a front elevation of the device, the near side of the buck being removed for the sake of clearness.

The form of the invention herein disclosed comprises a back member 3 in the shape of a bar adapted to span the open side of the steel buck indicated at 4 and a supporting arm 5 projecting from said back member. The supporting arm is shown as an angularly bent strip having one leg 6 overlying the face of the back strip and secured thereto by rivets 7, 8, the other leg forming the supporting arm 5. The end 9 of the portion 6 extends beyond the securing rivet 8 and is shown as flared outwardly to form with the back piece, a wedge-like opening to receive the edge 10 of the buck. The rivet 8 at the tip of this opening forms a stop for engagement with the edge of the buck to positively position the back strip laterally with respect to the buck.

At the opposite end the back member is secured to the opposite edge 11 of the buck by a clamp plate 12 overlying and adjustably secured to the back piece by screw 13. This clamp plate is indicated as slotted at 14 to allow for various adjustments of the clamp plate and to permit said plate being slid

back clear of the edge of the buck as indicated at 12a.

The outlet box, switch box or the like indicated at 15 may be secured to the supporting arm in various ways. It is shown in the illustration as having two sets of spaced hoes 16 therein to receive, in various relations, securing screws 17 passed through the bottom of the box. This method of fastening enables the box being supported at different distances away from the buck and the adjustable clamp structure enables the box being supported at different heights in respect to the buck.

In order that the box may be supported in different positions laterally of the buck, the supporting arm 5 is shown as positioned off center in respect to the clamp structure so that when the box is applied to one face of the supporting arm, as indicated in the full lines, it will be properly positioned for one wall surface 18 and when supported on the back of the arm, as indicated in broken lines, it will be positioned for a different wall surface 19, the latter being for instance a tile wall and the former being for example, an ordinary plaster surface.

The bracket is easily applied by entering the back piece through the open side of the buck and turning it horizontally so as to bring the fixed clamp at one end of the base piece over one edge of the buck, after which the clamp piece 12 is shifted to overlap the front of the opposite edge of the buck piece and the screw then tightened to make said clamp secure. The tightening of this clamp also has a wedging effect, since the clamp stands at an angle to the back piece and operates as it is tightened to force the clamp at the opposite end the more firmly into engagement with the buck. An interlock with the buck is thereby secured which fastens the bracket rigidly and firmly in place, holding it immovable even under the rough treatment which such devices are liable to receive.

What is claimed is:

1. A bracket for supporting an outlet box or the like from a steel buck comprising a member adapted to span the open side of the buck, said member having means at one end to grip one edge of the buck and provided

at the opposite end with an adjustable clamp for gripping the opposite edge of the buck in various positions of adjustment of the bracket on the buck and box supporting means carried by said member and including a box-supporting arm projecting away from the buck-engaging member, disposed off-center with respect to the buck and adapted to support a box at either side thereof and in different relations to the center of the buck.

2. A bracket for supporting an outlet box or the like from a steel buck comprising a back strip adapted to be engaged behind the edges of the buck, a strip bent at an angle to form two legs, one leg being secured to the face of the back strip and having its end positioned to overlie one edge of the buck, the other leg extending at an angle from the face of the back strip and forming a projecting box supporting arm and means for clamping the back strip to the opposite edge of the buck.

3. A bracket for supporting an outlet box or the like from a steel buck comprising a back strip to engage behind the edges of the buck, a strip bent at an angle to form two legs, one leg overlying and secured to the face of the back strip and the other leg projecting away from the back strip to form a box supporting arm, the end of the overlying portion being spaced from the back strip to engage over one edge of the buck and clamp means on the back strip for engagement over the opposite edge of the buck.

4. A bracket for supporting an outlet box or the like from a steel buck comprising a back strip to engage behind the edges of the buck, a strip bent at an angle to form two legs, one leg overlying the face of the back strip and the other leg projecting away from the back strip to form a box supporting arm, the end of the overlying portion being spaced from the back strip to engage over one edge of the buck, clamp means on the back strip for engagement over the opposite edge of the buck and a fastening for securing the angled strip to the back strip, said fastening being positioned to engage the edge of the buck and act as a positioning stop.

5. Outlet box supporting means comprising a member provided with means for slidably retaining the same to the opposite edge portions of a steel buck and adjustable to rigidly secure said member at different selected heights on the buck and means carried by said member for supporting an outlet box at different distances away from the open side of the buck and in different positions laterally of the buck.

6. A bracket for supporting a switch box or the like from a hollow steel buck having oppositely inturned edges at the open side of the same and comprising a member to be received in and extend across the open side

of the buck, a fixed clamp on said member opening outwardly at one end of the member to hook over one of the inturned edges of the buck, an adjustable clamp on the member opening outwardly at the opposite end of the member and adjustable on said member in inclined relation toward said member to close over the opposite edge of the buck and an angularly projecting arm carried by said member for supporting a switch box or the like positioned in desired relation to the open side of the buck with which the bracket is engaged.

7. A bracket for supporting a switch box or the like from a hollow steel buck having oppositely inturned edges at the open side of the same and comprising a member to be received in and extend across the open side of the buck, reversely facing outwardly opening clamp members at opposite ends of said member inclined to the longitudinal axis of said first-mentioned member and engageable over the inturned edges of the buck to securely anchor said member against vertical displacement on the buck and an angularly projecting arm carried by said member for supporting a switch box or the like positioned in desired relation to the open side of the buck.

8. A bracket for supporting a switch box or the like from a hollow steel buck having oppositely inturned edges at the open side of the same and comprising a member to be received in and extend across the open side of the buck, a positioning clamp adjacent one end of said member and engageable with one of the inturned edges at the open side of the buck to definitely position said member laterally of the opening in the side of the buck, a loose clamp plate positioned against the face of the member adjacent the opposite end of the same and engageable over the opposite inturned edge of the buck, a screw for forcing said clamp plate toward said member and for adjustably securing said clamp plate in gripping engagement over the opposite inturned edge of the buck and an angularly projecting arm carried by the member for supporting a switch box or the like positioned in desired relation to the open side of the buck.

9. A bracket for supporting a switch box or the like from a hollow steel buck having oppositely inturned edges at the open side of the same and comprising a member to be received in and extend across the open side of the buck, a clamp on said member opening outwardly at one end of the same to hook over one of the inturned edges at the open side of the buck, an adjustable screw clamp on said member opening outwardly at the opposite end of the same and shiftable to engage with an adjustable grip over the opposite inturned edge of the buck and a supporting arm projecting angularly away from said member

and constructed to support a switch box or the like in a variety of different positions relative to the open side of the buck.

10. A bracket for supporting a switch box or the like from a hollow steel buck and comprising a substantially flat back strip adapted to bridge the open side of the buck, a jaw extended outwardly from the face of said back strip adjacent one end of the same and 10 cooperating therewith to form an outwardly facing clamp engageable over one of the in-turned edges at the open side of the buck, a loose clamp plate overlying the face of the back strip adjacent the opposite end of the 15 same, a screw for fastening said loose clamp plate in overlying relation on the face of the back strip and forming with said back strip an outwardly opening adjustable clamp for gripping engagement over the opposite in-turned edge of the buck and a box supporting arm projecting at an angle from the face of the back strip and having an angularly turned foot portion rigidly secured over the 20 face of the back strip.
25. 11. Means for mounting an outlet box, on a hollow steel frame having flanges extending toward each other from the side walls of the frame but leaving an elongated opening between the flanges comprising, a plate to be received in and extend across the open side of the frame with its end portions in engagement with the inner surfaces of the flanges of the frame, securing means on the plate for engagement one flange of the frame, adjustable securing means on the plate for engaging the other flange of the frame, and means extending from the plate substantially at right angles thereto for supporting a box at different distances from the plate.
40. 12. Means for mounting an outlet box on a hollow steel frame having flanges extending toward each other from the side walls of the frame but leaving an elongated opening between the flanges, comprising, a plate to be received in and extend across the open side of the frame with its end portions in engagement with the inner surfaces of the flanges of the frame, securing means on the plate for engaging one flange of the frame, securing means on the plate for engaging the other flange of the frame and an arm extending from the intermediate portion of the plate between the flanges of the hollow steel frame and at an angle to the plate for supporting an outlet box or the like at different distances from the plate.
35. 13. A bracket for supporting a switch box

or the like from a hollow steel buck and comprising a substantially flat back strip adapted to bridge the open side of the buck across the in-turned flanges of the same, jaw members on said back strip opening outwardly toward opposite ends of the back strip and positioned to form with the back strip outwardly facing clamps to grip the in-turned flanges of the steel buck and an arm projecting at an angle from the face of the intermediate portion of the back strip between the buck flanges for supporting an outlet box or the like at a desired distance from the open side of the door buck.

14. Adjustable supporting means for attaching an electrical fitting to a channel-shaped metal frame, comprising a carrier in the form of a bar for spanning the opening in said frame, means at opposite ends of the bar for engaging said frame, said means including a clamp carried by the bar and adjustable thereon in a direction parallel with the axis of the bar, a supporting member carried by the bar and located thereon to position and support the electrical fitting in definite relation with the opening in the frame and means for supporting an article on said supporting member and constructed to enable the article being adjusted in a direction parallel with the axis of the supporting member.

15. Means for attaching an electrical fitting to a steel door buck, whereby the fitting may be quickly positioned so as to be at the proper height from the floor line, a suitable distance from the buck and in the right position with respect to the plaster finish line, comprising, a carrier extending across the opening between the in-turned flanges of the door buck, said carrier provided with clamps for gripping the flanges of the buck and at least one of said clamps being slidable on the carrier for enabling quick adjustment of the vertical position of the carrier on the buck in respect to the floor line, a supporting member mounted on and at right angles to the carrier and located to position the supported fitting in definite relation to the plaster finish line and means associated with said supporting member for securing the fitting thereon, so that the latter may be quickly located and secured in position at the desired distance from the buck.

In witness whereof, I have hereunto set my hand this 11th day of September, 1926.

WILLIAM L. LADEMANN.
